UNITED STATES PATENT OFFICE.

JOHN McHENRY, OF McDONALD, PENNSYLVANIA.

MAIL-BAG CATCHER AND DELIVERER.

SPECIFICATION forming part of Letters Patent No. 319,287, dated June 2, 1885.

Application filed April 21, 1885. (No model.)

To all whom it may concern:

Be it known that I, JOHN McHENRY, a citizen of the United States, residing at McDonald, in the county of Washington and 5 State of Pennsylvania, have invented certain new and useful Improvements in Mail-Bag Catchers and Deliverers; and I do hereby declare the following to be a full, clear, and exact description of the invention, such as will 10 enable others skilled in the art to which it appertains to make and use the same.

My invention relates to certain improvements in apparatus for catching mail-bags from a supporting-crane at a station, and at 15 the same time delivering one or more mail-bags from a passing train.

It consists in certain novelty of construction and arrangement of the receiver and deliverer secured to the car, and of the stationary supporting-crane and receiver at the station, all 20 of which I will now proceed to point out and describe, reference being had to the accompanying drawings, in which—

Figure 1 is a perspective of my invention, 25 showing the various parts in position to receive and deliver the mail-bags, said mail-bags being shown in dotted lines. Fig. 2 is a top plan view of the supporting-crane and receiver at the station and of a car provided 30 with my invention, the top of the car being removed and the mail-bags in position to be delivered and received. Fig. 3 is a side elevation showing the car after it has passed the supporting-crane and the mail-bags have 35 been received and delivered. Fig. 4 is a detail.

Referring to said drawings, A is a railway-track; B, a stationary frame adjacent to the track; C, a receiving-frame hinged at one end 40 to the frame B at b.

c are wires forming a spring-bottom for the frame, into which the mail-bags drop, as hereinafter described.

c' is a metal support hinged to the free end 45 of the receiving-frame. When in position to receive a mail-bag, the free end of the frame C is raised, and the support c' rests on a spring-arm, c'', thus giving said frame a slight spring when the mail-bags fall upon it. The

support c' may be of any desired height. 50 When not in use the frame is lowered to the position shown in dotted lines, Fig. 3.

D is a vertical stationary frame secured to the frame B.

d' are projecting arms, forming, in combination with the frame D, supporting-cranes, on one of which a mail-bag is received and from the other a mail-bag is delivered.

d'' are delivering-arms hinged at one end to the frame D, the upper arm being supported, 60 when in position to deliver a mail-bag, by the arm d', the lower arm by the pin d''. A mail-bag is hung on the outer ends of these arms, as shown in Figs. 1 and 3. As the receiver on a passing car catches the bag, the arms 65 are knocked off their supports and fall to the position shown in Fig. 3.

E is a triangular-shaped frame hinged to the frame D.

E' is a receiving-needle on the end of the 70 frame E. Said needle is adapted to engage with a loop on a mail-bag, which is hung on the deliverer of a passing car and catches said mail-bag as the car passes. The needle is held in place by a projection, e, engaging 75 with a pin, e'. When not in use, it is turned back to the position shown in dotted lines, Fig. 2.

e'' is a projection on the arm d, which engages with the detaching-lever of the deliverer 80 on a car, for a purpose hereinafter described.

F is a railway-car; f, a door in the same. A similar door is provided on the opposite side of the car.

G is a removable crane, having the post g, 85 mounted in suitable bearings, g' g'', on the inside of the car, and also provided with the compound arm G', composed of two sections, H H', hinged together at the elbow h, the section H being rigidly secured at a right 90 angle to the post g.

I is a basket or mail-bag receiver secured to the outer end of the section H'. To use the receiver the post g of the crane is rotated on its bearings, the compound arm being bent 95 and the basket or receiver passed out through the door until the section H is parallel with the side of the car and rests against the bear-

ing f' , the section H' resting against the side of the door-frame and bearing f^2 , which forms a strong support for the same.

The post g , being removable can be taken down and placed in suitable bearings on the opposite side of the car, the receiver projecting out through the opposite door. It will thus be seen that the device can be used on either side of a car.

10 If desired, two compound arms and receivers could be secured to the post of the crane, thus doubling the number of mail-bags that can be received and delivered.

K is a delivering-frame rigidly secured to the rear of the receiving-basket.

15 k is a supporting-hook located about the center of the frame. On this hook a mail-bag is hung.

K' is an arm hinged at one end to the side 20 of the frame K . Said arm K' is provided with an eye, k' , which fits over the hook k . The outer end of the arm projects over the outer side of the frame K .

25 L is a weighted detaching-lever pivoted to the outer end of the compound arm G' . Said lever is provided with an upwardly-projecting arm, l , which engages with the projection e^2 on the supporting-crane at the station when the lever is adjusted for use.

30 M is an upwardly-projecting hook secured to the center of the frame K . On this hook a mail-bag, N , is hung. Said bag is provided with a loop, n , which is adapted to be caught by the receiving-needle E' .

35 O and P are mail-bags.

My invention is operated as follows: As the train approaches a station, a mail-bag similar to N and provided with a loop, n , is hung on the hook M . If there are two bags to be delivered, 40 place the eye of arm K' over the hook k , adjust the weighted lever L so that its end will be behind the end of the arm K' , then hang a bag on said hook k . The compound arm G' is then moved out through the door to position 45 shown in Figs. 1 and 2.

At the station the receiving-frame C is raised, as shown, and a mail-bag hung on the arms d^2 . As the train passes the stationary crane, the needle E' engages with the loop n 50 and lifts the same off the hook, and the upper projecting arm of the detaching-lever strikes the projection e^2 on the stationary crane and forces the arm K' and mail-bag off the hook k , the bag dropping into the receiving-frame C , which holds said bag and prevents it from 55 falling under the train. Simultaneously with this operation the mail-bag P is caught by the receiving-basket I , and after the train has passed the station the compound arm and receiver are drawn within the car, as shown in 60 dotted lines, Fig. 2.

Having thus fully described my invention, I claim as new and desire to secure by Letters Patent—

1. In a stationary apparatus for catching 65 mail-bags, a receiving-frame hinged at one end to a stationary frame and provided with a spring-bottom and an adjustable support, substantially as and for the purpose shown and described.

2. In a stationary apparatus for catching mail-bags, a receiving-frame, C , hinged at one end to a stationary frame and provided with an adjustable support, c' , in combination with a spring-arm, c^2 , substantially as and for the 75 purpose set forth.

3. A stationary crane for receiving mail-bags, provided with a frame, E , hinged to said crane, having a projecting receiving-needle, E' , substantially as and for the purpose shown 80 and described.

4. In a mail-bag catcher, a swing-crane mounted in suitable bearings on the inside of a car, and provided with a compound arm composed of two sections hinged together and 85 having a receiving-basket on the outer end of said arm, substantially as and for the purpose shown and described.

5. In a mail-bag catcher, the removable crane composed of the post g , mounted in 90 suitable bearings on the inside of a car, and the compound arm G in two sections, H H' , provided with the receiving-basket I on the outer end of said arm, all arranged substantially as shown and described, as and for the 95 purpose set forth.

6. In a mail-bag deliverer, a swinging crane mounted in suitable bearings on the inside of a car, and provided with a compound arm, G' , having secured to its outer end the frame K , 100 having the supporting-hook k , in combination with the arm K' , provided with the eye k' , and the detaching-lever L , having the projecting arm l , all arranged and operating substantially as and for the purpose set forth.

7. In a mail-bag deliverer, a swinging crane mounted in suitable bearings on the inside of a car, having the compound arm G' , provided with the supporting-hook M , substantially as 105 and for the purpose shown and described.

8. In a mail-bag catcher and deliverer, a swing-crane mounted in suitable bearings on the inside of a car, and having a compound arm, G' , provided on its outer end with a receiving-basket, I , and a frame, K , having the 110 delivering-hook k , in combination with the arm K' , and the detaching-lever L , having the projecting arm l , all arranged and operating substantially as shown and described.

In testimony whereof I affix my signature 115 in presence of two witnesses.

JOHN McHENRY.
